Primary Examiner — Richard E Chilcot

(57) **CLAIM**

The ornamental design for a drilling tool, as shown and described.

DESCRIPTION

1. Drilling tool

1.1 : Right

1.2 : Front

1.3 : Left

1.4 : Back

1.5 : Top

1.6 : Bottom

1.7 : Perspective

Surface mountable drilling machine.

The broken lines are included for the purpose of illustrating portions of the drilling tool that form no part of the claimed design.
